UNITED STATES PATENT OFFICE

2,227,032

CATHODE RAY TUBE

Kurt Schlesinger, Berlin, Germany, assignor, by
mesne assignments, to Loewe Radio, Inc., a cor-
poration of New York

Application March 30, 1938, Serial No. 198,828
In Germany April 4, 1932

3 Claims. (Cl. 250—27)

The present application is a continuation-in-part of my co-pending application Serial No. 663,593 filed in the United States Patent Office on March 30, 1933. The said application Serial No. 663,593 is now abandoned.

The present invention relates to cathode ray tubes and more particularly to tubes having an indirectly heated equipotential cathode. The emissive spot of the cathode consists preferably of a recess in the end part of the minute cathode tube which recess is filled with emissive material.

It is well known that an emissive surface of the described kind does not furnish an emission of equal intensity on the whole surface and that the point of maximal emission intensity even varies with the integral intensity of the ray, thus depending on the anode voltage or on the ray controlling potential. Also the apparent form of the spot depends on the same variables so that the focal distance and consequently the sharpness of the luminous point on the screen varies.

It is an object of the invention to avoid the above faults by a special electrode arranged close to the cathode.

The invention is illustrated in the accompanying drawing in which—

Figs. 1, 1a and 3 show arrangements of tube electrodes according to the invention, whilst

Fig. 2 shows the apparent form of the cathode as produced by the new cathode.

In Figs. 1 and 3, 11 is the cathode heated by the resistance 12 and provided with the emissive spot 14. 13 is a diaphragm acting as anode. The electrode according to the invention is a cylinder or ring 15 surrounding the cathode at its end very closely and overwhelming it only a little. In Fig. 1, the space between cathode and cylinder 15 has been exaggerated in order to show the virtual equipotential plane 16 when 15 is provided with a potential a little more negative than the cathode. The distribution of potentials is indicated by connection of the electrodes to a potentiometer 21. By the effect of the electrode 15 the apparent surface of the cathode, from the point of view of the first anode 13 and the subsequent electron-optical device (not illustrated), is as shown in Fig. 2.

In order to concentrate the electron ray the

cathode may further be surrounded in the usual way by a Wehnelt cylinder 17 as shown in Fig. 1a. Such cylinder may, also as usual, control the intensity of the ray by connecting the cylinder to the potentiometer 21 through a resistance 23 and to the intensity control potential 24 through a condenser 22.

According to the invention it is also possible, as shown in Fig. 3, to give a constant negative potential to the Wehnelt cylinder 17 and to control the intensity of the ray for television purposes by means of the electrode 15. In this case 15 is biased negatively towards the cathode via a high resistance 23 and connected to the output 24 of the receiver via a condenser 22.

I claim:

1. In a cathode ray tube comprising an equipotential cathode having an electron-emissive spot, and a Wehnelt cylinder having a negative bias with respect to said cathode and connected to a ray controlling variable potential, an electrode consisting of an annular cylinder which is surrounded by said Wehnelt cylinder and itself closely surrounds the electron-emissive spot of said cathode and means to impart to said inner cylinder a slight negative potential with respect to said cathode.

2. In a cathode ray tube comprising an equipotential cathode having an electron-emissive spot, and a Wehnelt cylinder having a negative bias with respect to said cathode, an electrode consisting of an annular cylinder closely surrounding the electron-emissive spot of said cathode and means to impart to said cylinder a slight negative potential with respect to said cathode.

3. In a cathode ray tube comprising an equipotential cathode having at its end a recess filled with electron-emissive material to form an electron-emissive spot and a Wehnelt cylinder having a negative bias with respect to said cathode, an electrode consisting of an annular inner cylinder which is surrounded by said Wehnelt cylinder and itself closely surrounds the electron-emissive spot of said cathode, means to impart to said cylinder a slight negative bias with respect to said cathode and means to connect one of said negative electrodes with a ray controlling variable potential.

KURT SCHLESINGER.
